UNITED STATES PATENT OFFICE

WILLIAM P. SPRAGUE, OF LOS ANGELES, CALIFORNIA

CLASP

Application filed February 14, 1931. Serial No. 515,832.

My invention relates to and has for its purpose the provision of a clasp of simple, substantial, and compact construction, which in one of its many uses, is adapted to securely and neatly hold in place, one or more folds of cloth gathered at one point or from two separate points, so that in the application of the clasp to a shirt sleeve of excessive length for example, the sleeve can be maintained shortened as required to accommodate the arm length of the wearer, all without detracting from the appearance of the sleeve.

I will describe only one form of clasp embodying my invention, and will then point out the novel features thereof in claims.

In the accompanying drawings:

Figure 1 is a view showing in front elevation, one form of clasp embodying my invention applied to a fold in the sleeve of a shirt. Figures 2 and 3 are vertical sectional views taken respectively on the lines 2-2 and 3-3 of Figure 1, and

Figure 4 is a perspective view of the clasp in open position.

Referring specifically to the drawings in which similar reference characters designate similar parts in each of the several views, my invention in its present embodiment comprises a pair of hingedly connected and co-acting members M and M', the member M being formed from a length of wire into substantially T-shape to provide a hinge pin 10 from the ends of which project at a right angle, parallel branches 11 and 11^a each of which is extended laterally at a right angle to provide oppositely projecting clamping branches 12 and 12^a respectively, terminating in return bends 13 and 13^a respectively, connected by a rectilinear portion 14 disposed parallel to the pin 10 and constituting the latching element of a latch embodied in the clasp for releasably retaining the members M and M' in the closed position shown in Figures 1, 2, and 3.

The member M' is constructed from sheet metal to provide a rectangular body 15 having one end curled upon the pin 10 to form a sleeve 16 co-acting with the pin to hingedly connect the members. The sleeve is of less length than the width of the body to provide

shoulders 17 constituting stops with which the member M co-acts to limit the open position of the members. The opposite end of the member M' is curved laterally as indicated at 18 and its free extremity is bent upon itself to provide a groove 19 constituting a keeper into which the rectilinear portion 14 of the member M is adapted to be sprung or snapped to latch the members closed.

The body 15 is provided intermediate its ends with right angularly projecting clamping arms 20 and 20^a. The corners of these arms at their free extremities are rounded, and the arms are curved longitudinally as shown in Figure 4, so that when the members M and M' are closed, the arms will project beyond the plane of the member M and will co-act with the clamping branches 12 and 12^a of the latter to clampingly engage a fold of cloth in a manner to be later described.

The operation of the clasp in its application to the sleeve of a shirt in order to shorten the sleeve, is as follows:

The shirt sleeve is first folded transversely upon itself at the desired location along its length a sufficient amount to produce the desired shortening of the sleeve length as shown in Figures 1 and 2, after which the free end of the member M is inserted between the main body 21 of the sleeve and the fold 22 as shown in Figure 2. The member M' is now closed upon the member M, causing the fold to be tightly clamped at its juncture with the main body of the sleeve, as the rectilinear portion 14 of the member M and the groove 19 of the member M' co-act to latch the members closed with the fold of the fabric interposed therebetween.

When the members are latched closed, the clamping branches 12 and 12^a of the member M will co-act respectively with the clamping arms 20 and 20^a of the member M', to securely clamp the fold 22 at opposite sides of the latch formed by the rectilinear portion 14 and the groove 19, so as to prevent sagging of the fold and possible unfolding of the latter as well as tilting of the clasp on the sleeve.

With the fold thus clamped at three locations, it will be maintained flat against the

main body of the sleeve for a considerable distance around the sleeve from opposite sides of the clasp to insure neatness in appearance. The clasp is shaped to generally 5 follow the curvature of the arm, and sufficient space exists between the members M and M' to receive several thicknesses of fabric so that more than one fold can be gathered at a single location or from separate 10 locations. The clasp is capable of many uses, such as securing a stocking to other wearing apparel; holding down a shirt front; and clamping together sheets of paper or fabric.

15 Although I have herein shown and described only one form of clasp embodying my invention, it is to be understood that various changes and modifications may be made therein without departing from the spirit 20 of the invention and the spirit and scope of the appended claims.

I claim:

1. A clasp of the character described comprising two members, means on one end of 25 the members for hingedly connecting the latter to occupy a closed position and an open position to permit the insertion of a piece of material between the members, means on the free ends of the members co-acting to clamp 30 the material between the members and to latch the latter closed, and means projecting laterally from opposite sides of the members intermediate their ends, co-acting to clamp the material when the members are 35 latched closed.

2. A clasp of the character described comprising two members, means on one end of the members for hingedly connecting the latter to occupy a closed position and an open 40 position to permit the insertion of a piece of material between the members, means on the free ends of the members co-acting to clamp the material between the members and to latch the latter closed, and means projecting laterally from opposite sides of the members intermediate their ends, co-acting to clamp the material when the members are 45 latched closed, the last means comprising lateral branches on one member and lateral 50 arms on the other member curved longitudinally to pass beyond the planes of and in close proximity to said branches in the closed position of the members.

3. A clasp of the character described comprising a member constructed from a length 55 of bendable wire to provide a hinge pin having parallel spaced apart branches projecting therefrom and extended in opposed directions to provide clamping branches terminating in return bends and a rectilinear portion connecting the latter and disposed parallel to the pin, a second member constructed from sheet material to provide an elongated body having a sleeve at one end 60 receiving the pin to hingedly connect the

members, and bent upon itself at its opposite end to form a groove co-acting with said rectilinear portion to clamp a piece of material and latch the members closed, and means on the second member co-acting with 70 said clamping branches to additionally clamp the material when the members are latched closed.

4. A clasp as embodied in claim 3 wherein the last means comprises arms projecting laterally from the second member intermediate its ends and curved longitudinally to pass beyond the planes of and in proximity to said branches when the members are closed.
